J. A. HATTIE

NUT FOR GUITARS

Filed Feb. 3, 1923

UNITED STATES PATENT OFFICE.

JAMES A. HATTIE, OF EWA, TERRITORY OF HAWAII.

NUT FOR GUITARS.

Application filed February 3, 1923. Serial No. 616,789.

To all whom it may concern:

Be it known that I, JAMES A. HATTIE, a citizen of the United States of America, residing at Ewa, in the Territory of Hawaii, 5 have invented new and useful Improvements in Nuts for Guitars, of which the following is a specification.

The object of this invention is to provide a musical instrument, such as a guitar, with a 10 nut having simple and effective means for raising the strings from the finger board over the frets to a determined height, and to likewise lower the strings from such elevation to original position when desired, thus providing 15 a means which permits the playing of the guitar as an accompanying instrument and likewise playing the same as a steel guitar.

A further object of the invention is to 20 eliminate the necessity of slackening all of the strings on a guitar for the purpose of introducing a higher nut as is now the custom when a person desires to switch from the ordinary tuning to the tuning for steel 25 guitar playing.

To the attainment of the foregoing and other objects which will present themselves as the nature of the invention is better understood, reference is to be had to the 30 drawing which accompanies and which forms part of this application.

In the drawing:—

Figure 1 is a plan view showing a portion 35 of the neck and head of a guitar provided with the improvement.

Figure 2 is an approximately central vertical longitudinal sectional view therethrough, the dotted lines showing the rest in raised position.

40 Figure 3 is a transverse sectional view through the improvement.

Figure 4 is a perspective view of the movable rest member.

Figure 5 is a similar view of the screw 45 with the follower blocks thereon.

Figure 6 is a similar view of the hollow base member.

As disclosed by the drawings, my combination guitar nut includes a hollow base 50 1 open only at its top. The ends of the hollow base 1 are provided with aligning non-threaded openings that receive therethrough and provide guides for a screw 2. On one end of the screw there is an operating head 3, and on the other end of the

screw there may be secured a cap 4 that prevents the sliding of the screw through the openings in the body therefor. In the body there is a pair of spaced blocks 5 having threaded openings therethrough engaged 60 by the screw, and the upper or outer faces of these blocks are beveled, as at 6. The blocks are in the nature of follower members as the same will be moved longitudinally in the hollow base upon the turning 65 of the screw 2. The blocks are held from lateral movement by contacting engagement with the sides and with the bottom of the hollow base element 1.

The movable member or string rest of 70 the nut is indicated by the numeral 7, the same having its outer face rounded and notched for the reception of the strings of the guitar. The rest 7 has flanged sides 8 received through the top of the hollow base, 75 and the said sides have their lower edges cut to provide spaced inclined surfaces 9 and 10 respectively designed for contacting engagement with the inclined faces of the follower blocks 5. The sides, at the terminal of the 80 beveled surfaces 10 are straight, as at 11, the inner wall between the said sides 11 being rounded, as at 12, and the said portions 11 straddling the screw and form stops for the movement of one of the blocks 5 85 longitudinally in the body. By turning in one direction the follower blocks 5 are caused to move longitudinally on the screw, the beveled faces thereof riding under the beveled portions 9 and 10 of the movable 90 member 7 of the bridge causes the same to be moved to a raised position. By turning the screw in an opposite direction the member 7 and the strings supported thereon will be lowered. Thus, it will be seen that the 95 improvement provides for the playing of the guitar as an accompanying instrument as well as the playing thereof as a steel guitar.

When the strings are raised for playing 100 the instrument as a steel guitar, sufficient clearance is afforded for the steel bar used for this purpose so that the same will slide up and down the strings without coming in contact with the ends of the frets. It will 105 be noted that the rise of the string rest of the nut is slow and gradual which avoids breaking the strings which are already in tense condition. It is to be understood that the device may be constructed of any de- 110

sired material and that the sizes thereof may be altered to conform with the size of the neck of the various makes of guitars at the point where the bridge is naturally used.

5 It is also to be understood that this device is designed for use on instruments, other than a guitar, as a nut to lower or raise the strings of said instruments to decrease or increase the tension of the strings to satisfy 10 the individual touch.

Having described the invention, I claim:—

1. A nut for stringed instruments comprising a hollow base, a channeled string rest in the base having the edges of its sides 15 formed with spaced inclined walls, follower members in the base on which the inclined walls rest, and revoluble means operated at one end of the base and engaging with the follower members for moving the same 20 longitudinally in the base and by virtue of

such movement to raise or permit the lowering of the string rest on the base.

2. A nut for stringed instruments including a hollow base and a channeled string rest designed to be received in the base to 25 contact with the side and end walls thereof, the sides of said channeled member having their sides stepped and the lower walls provided by the steps arranged at the same angle, a headed screw finding bearings in 30 the ends of the base and received centrally between the side walls of the rest member, follower blocks in the base having upper inclined surfaces to engage with the inclined stepped portions of the rest and having 35 threaded openings engaged by the screw for the purpose set forth.

In testimony whereof I affix my signature.

JAMES A. HATTIE.
